UNITED STATES PATENT OFFICE.

EWELL E. FOWLER, OF EAST POINT, GEORGIA, ASSIGNOR TO UNDERWOOD TYPEWRITER COMPANY, OF NEW YORK, N. Y., A CORPORATION OF DELAWARE.

TYPEWRITING MACHINE.

Application filed April 10, 1920. Serial No. 372,968.

To all whom it may concern:

Be it known that I, EWELL E. FOWLER, a citizen of the United States, residing in East Point, in the county of Fulton and 5 State of Georgia, have invented certain new and useful Improvements in Typewriting Machines, of which the following is a specification.

This invention relates to paper-handling 10 devices for typewriting machines, and is herein illustrated as especially adapted for use in an Underwood standard bookkeeping machine, which is used both for making out statements and entering the items upon 15 ledgers.

In such machines, the columns in which computing is done are determined by selectors or denomination-selecting dogs upon the carriage, adapted to be adjusted to various 20 columns. Since such machines are usually put into the hands of typists who know nothing of machinery and find the adjustment of such dogs annoying, it is advantageous to so position the columns upon 25 ledger sheets and statement sheets that the selectors or dogs when once adjusted will serve for computing purposes when either a ledger sheet or a statement sheet is being typed. Usually the ledger sheet and statement 30 sheet are of different widths or the columns are differently positioned on the two kinds of sheets, with the result that, to avoid shifting the selectors, it has often been necessary to readjust the paper gages 35 customarily employed, when changing from one kind of sheet to the other.

According to the present invention, it is unnecessary to adjust a gage each time the shift is made from statement to ledger writing, or vice versa. The usual form of side 40 gage may be employed for inserting one kind of sheet, and a second side gage or auxiliary gage may be used when inserting the other kind of sheet. The second or auxiliary 45 gage may be set to ineffective position by actuation of a finger-piece when it is desired to use the usual gage for the wider sheets. The auxiliary gage may be adjustable to suit various types of work, but when 50 once adjusted for any form of work that adjustment need not be disturbed in any usual office routine.

When built to be used in connection with 55 one ordinary form of gage and paper-table, the auxiliary gage may take the form of a

flat plate having a turned-up gaging end extending through an elongated opening in the front paper-table, thus permitting the turned-up end to be adjusted within the limits of the opening. A spring may normally tend to hold the turned-up end above the level of the paper-table, so that it may be used for gaging purposes. Whenever it is desired to use the usual gage at the end of the table, the turned-up end may be shifted to ineffective position by actuation of a finger-piece which withdraws it behind the table.

Other features and advantages will hereinafter appear.

In the accompanying drawings,

Figure 1 is a fragmentary sectional side view of an Underwood standard typewriter carriage, showing the present invention as applied thereto.

Figure 2 is a fragmentary front view of the auxiliary gage and the finger-piece for actuating it.

Figure 3 is a sectional side view, showing the auxiliary or temporary gage in effective 80 position.

Figure 4 is a similar view, showing the temporary gage in ineffective position.

Figure 5 is a plan view of most of the parts seen in Figure 6.

Figure 6 is a front view of a carriage embodying the present invention, with many parts omitted or broken away.

In the Underwood standard typewriting machine carriage, a platen 10 is journaled 90 by its axle 11 in a shift-frame 12, and, in the form herein illustrated, is provided with feed-rolls 13 and 14, which are adapted to hold against the platen work-sheets fed down over the rear paper-table 15, so that 95 they bend up in front past the printing line at the type-head diagrammatically shown at 16. The platen is rotated by the usual line-space handle 17, which is effective, through a slide 18, upon the line-space wheel 19 fast to 100 the axle 11.

When the typist inserts a work-sheet over the paper-table 15 in the manner described, she customarily throws off the feed-rolls 13 and 14 by depressing the usual feed-roll release handle 20, which casts off the feed-rolls 13 and 14 by actuating the casting-off mechanism through the usual link 21. Then the typist passes the work-sheet forward past the printing line at 16, and, in the case 110

2
of one sheet, which may be a ledger sheet, gages the right-hand edge of it against a side gage 22, forming part of a front paper-table 23, which is supported above the platen 5 and in front thereof by a tie-rod 24 extending across the frame 12. The paper-table 23 is usually set in position for the standard work of any office by set-screws 25, which pass through collars 26 to engage the tie-rod 10 24, and which support brackets 27 to which the table 23 is detachably held by a cross-bar 28 having openings 29 adapted to engage headed studs 30.

For the first entry on the ledger sheet, the 15 ledger sheet may be gaged by an upper or leading-edge gage 31 at the upper end of the paper-table 23. Then the typist throws on the feed-rolls 13 and 14 and proceeds to type the entries. If, on the other hand, the typist 20 is making entries on other sheets, which may be statement sheets, usually narrower than the ledger sheets, the typist gages a statement sheet, after passing it around the platen in the usual manner, by bringing its 25 right-hand edge against a temporary gage 32 forming the turned-up end of a member 33, which projects through an elongated opening 34 in the paper-table 23. Normally, the gage 32 is held in the effective Figure 3 30 position, projecting through the opening 34, and, for this purpose, is formed as an extension of a resilient member 35 held by countersunk screws 36 to the paper-table 23. The resilient member 35 is offset from the 35 table by being bent rearwardly at 37; thus enabling a cam 38 to be swung between it and the table 23 to cam the gage 32 rearwardly to the Figure 4 position, in which the gage lies entirely behind the table and is 40 therefore ineffective. The cam 38 is formed as the turned-up extension of a plate 39, journaled upon a shouldered bolt 40 having a countersunk head 41, which passes through the table 23. The plate 39 has a bell-crank 45 extension 42, which extends up above the top of the table 23, and is bent over to form a finger-piece 43 adapted to swing the cam 38 between the Figure 3 and Figure 4 positions. Preferably the finger-piece 43 lies far 50 enough behind the gage 31 to prevent work-sheets from catching it. To enable the gage 32 to be adjusted transversely of the paper-table 23, the resilient member 35 is provided with a slot 44, so that screws 45, spaced a 55 little way apart in the extension 33, may pass through the slot and be threaded into a small plate 46 to bind the extension 33 to the resilient member 35 at any point along the length of the slot 44.

60 Variations may be resorted to within the scope of the invention, and portions of the improvements may be used without others.

Having thus described my invention, I claim:

65 1. In a typewriting machine, the combi-

nation with a platen and a paper-table having an opening, of a side gage upon the table, a resilient member behind the table and fast thereto, a turned-up end of said member projecting through an opening in said table 70 to form a second gage, a cam pivoted on the table between it and the member, and a finger-piece extending beyond the table for swinging the cam to make the second gage 75 ineffective at will.

2. In a typewriting machine, the combination with a platen and a paper-table having an elongated opening, of a gage upon the table, a resilient member behind the table, an adjustable extension of said member comprising a turned-up end, having a broad flat face and urged by said member to project through said opening to serve as a second gage, and means for overcoming said resilient member and making said second 80 gage ineffective at will.

3. In a typewriting machine, the combination with a platen and a paper-table having an elongated opening, of a gage upon the table, a resilient member behind the table, an extension of said member comprising a turned-up end having a broad flat face and adapted to project through said opening to serve as a second gage, a pair of screws sliding in slots to adjust the extension along the 90 member to adjust the second gage in the opening, and a manually-adjustable cam adapted to thrust the second gage clear of the opening to enable work-sheets to be 95 gaged to the first gage.

4. In a typewriting machine, the combination with a platen and a platen-frame, of a transverse bar in said frame, a front paper-table detachably supported on the bar, a leading edge gage at the top of said table, 100 a side edge gage at the side of the table, a second side edge gage positioned to project forwardly through an opening in the table, a resilient mounting for said second gage tending to hold the latter in projected position, a finger-piece shiftably mounted upon the table, and finger-piece-actuated means to 105 make the second gage effective and ineffective at will.

5. A paper-table adapted to be attached 115 to a typewriting machine comprising a leading-edge gage and a side edge gage, a temporary side edge gage having a broad flat face and projecting through an opening in the table, an adjustable mounting for the temporary gage to vary its position across the 120 table, and means, including a manually-operable cam, to make the temporary gage ineffective or effective at will.

6. The combination with a paper-table, of 125 a gage projecting through an elongated opening in said table and extending transversely thereof, means for adjusting said gage across the table in the opening, and means, including a finger-piece, for moving 130

the adjusted gage to and holding it in ineffective position behind the table without varying the adjustment thereof.

7. In a typewriting machine, in combination, a platen, a paper-table at the delivery side thereof, and side-gaging means adapted for rapid change for use with different forms of work-sheets, the side edges of which are to be gaged in different positions along the platen, said means comprising a side gage for work-sheets of one kind, a temporary side gage for work-sheets of a second kind, whose corresponding edges do not extend so far in the gaging direction as those of the first kind, a finger-piece visible and accessible from the front of the machine, and finger-piece-actuated means for controlling the movement of the temporary side gage to and from effective gaging position at the surface of the paper-table to enable, respectively, a sheet of the second kind or a sheet of the first kind to be side-gaged on the paper-table.

8. In a typewriting machine, in combination, a platen, a paper-table at the delivery side thereof, side-gaging means including a right side gage associated with said paper-table and a second right side gage at the left of the first, a finger-piece mounted behind the paper-table and extending beyond the limits thereof, so as to be accessible from the front of the machine, and finger-piece-actuated controlling means for said gaging means, whereby either the first-mentioned gage may be used to position a sheet of one kind lying substantially flat on the paper-table or the second-mentioned gage may be used to position a sheet of a second kind lying flat on said table.

9. In a typewriting machine, in combination, a platen, a paper-table at the delivery side thereof, side-gaging means for use at one side of two kinds of work-sheets, the respective side edges of which are to be gaged in two different positions along the platen, a manually-shiftable member movable backward and forward between two limiting positions, and means whereby movement of said member to one of said positions will render said side-gaging means effective for gaging a sheet of one of the said kinds resting on said paper-table, and movement to the other position will render the side-gaging means effective for gaging a sheet of the other kind.

10. In a typewriting machine, in combination, a platen, a paper-table at the delivery side thereof, side-gaging means for use at one side of two kinds of work-sheets, the respective side edges of which are to be gaged in two different positions along the platen, a manually-shiftable member movable backward and forward between two limiting positions, means whereby movement of said member to one of said positions will render said side-gaging means effective for gaging a sheet of one of the said kinds resting on said paper-table, and movement to the other position will render the side-gaging means effective for gaging a sheet of the other kind, and means for adjusting the side-gaging means to correspond to different distances of sheets.
